US00D744087S

(12) **United States Design Patent**
Bilgic

(10) **Patent No.:** **US D744,087 S**
(45) **Date of Patent:** **** Nov. 24, 2015**

(54) **DRY POWDER INHALER**

(71) Applicant: **Mahmut Bilgic**, Istanbul (TR)

(72) Inventor: **Mahmut Bilgic**, Istanbul (TR)

(**) Term: **14 Years**

(21) Appl. No.: **29/468,586**

(22) Filed: **Oct. 1, 2013**

(51) LOC (10) Cl. **29-02**

(52) U.S. Cl.

USPC **D24/110**

(57) **CLAIM**

The ornamental design for a dry powder inhaler, substantially as shown and described.

DESCRIPTION

FIG. 1 is a left elevation view of the dry powder inhaler.
FIG. 2 is a right elevation view of the dry powder inhaler.
FIG. 3 is a front side elevation view of the dry powder inhaler.
FIG. 4 is a back side elevation view of the dry powder inhaler.
FIG. 5 is a top plan view of the dry powder inhaler.
FIG. 6 is a bottom plan view of the dry powder inhaler; and,
FIG. 7 is a perspective view of the dry powder inhaler.

1 Claim, 7 Drawing Sheets
